CLAIM

The ornamental design for an garment for embroidery, as shown and described.

DESCRIPTION

FIG. 1 is a front perspective view of a first embodiment of a garment for embroidery showing the new design;

FIG. 2 is a front view of the first embodiment of the garment for embroidery shown in an alternate configuration with the top flap laid flat;

FIG. 3 is a back view thereof;

FIG. 4 is a top view thereof;

FIG. 5 is a bottom view thereof;

FIG. 6 is a right side view thereof;

FIG. 7 is left side view thereof;

FIG. 8 is a front alternate view of the first embodiment of the garment for embroidery shown in an alternate configuration with the top flap turned up;

FIG. 9 is a front perspective view of a second embodiment of the garment for embroidery;

FIG. 10 is a front view of the second embodiment of the garment for embroidery shown in an alternate configuration with the top flap laid flat;

FIG. 11 is a back view thereof;

FIG. 12 is a top view thereof;

FIG. 13 is a bottom view thereof;

FIG. 14 is a right side view thereof;

FIG. 15 is left side view thereof; and,

FIG. 16 is a front alternate view of the second embodiment of the garment for embroidery shown in an alternate configuration with the top flap turned up.

The broken lines depict portions of environment that form no part of the claimed design. The dash dot lines depict boundary lines of the claimed design.
